UNITED STATES PATENT OFFICE

2,635,588

BURNER FOR HEAVY FUELS

Marcel G. Bachem and André E. Taupenas,
Montelimar, Drôme, FranceApplication September 24, 1948, Serial No. 51,044
In France October 2, 1947

1 Claim. (Cl. 122—23)

1

The present invention has for object a burner for heavy fuels, characterised by the free combustion of the fuel in a cup in which it arrives drop by drop by gravity from a reservoir arranged at a higher level and having adjusting valve, the combustion being speeded by ventilation obtained without the aid of mechanical or electrical means, but by a jet of water vapour produced at low pressure. Preferably this vapour is produced by the apparatus itself, forming a less bulky assembly, and comprising a boiler crossed by a combustion tube in which is arranged the combustion cup in such a manner that the combustion tube, which is heated by the combustion, in turn heats the water contained about itself in the boiler. The feed of water to the boiler is by means of a constant level regulator. The pressure in the boiler and the regulator are made equal to ensure a constant feed whatever the pressure may be. An adjustable valve establishes the maximum pressure which can be present in the boiler and the water level regulator.

An example of construction of the invention is shown schematically in the accompanying drawing, wherein Figure 1 shows a perspective elevation of the burner; Figure 2 shows a central vertical section therethrough; Figure 3 shows a vertical section of the constant level regulator, to a larger scale.

The heavy fuel (light fuel-oil, domestic fuel-oil, or gas oil) is kept in a reservoir 1 placed at a higher level and provided with an escape pipe 2 to a valve 3 for adjustment of the flow. The fuel falls from the valve 3 into a funnel 4 which is extended by a vertical or oblique tube 5. This tube 5 crosses a combustion tube 6 and emerges above a cup 7 into which it allows the fuel to fall freely. It is in this cup 7 that the combustion of the fuel takes place and at first in free air. The cup 7 is simply placed in the combustion tube 6 and can be withdrawn by simple pulling to be cleaned of residues of the combustion or filled for lighting if need be.

If the burner consisted simply of this device forming a simple hearth, the combustion of the fuel would be slow with a feeble production of heat and a very great production of smoke.

To speed this combustion, a ventilation device is added to the simple hearth device, but this former does not require any mechanical or electrical force because of the fact that it employs a jet of water vapour at low pressure, the said jet drawing in ambient air. This water vapour is preferably produced by the apparatus itself which comprises a boiler 8 surrounding the com-

2

bustion tube 6, this latter being heated by the combustion of the fuel falling into the cup. Water contained between the walls of this boiler and the combustion tube can thus be heated and produce water vapour.

The boiler 8, of any shape (parallelepiped, cylindrical, or otherwise) has air-tight walls and is crossed from one part to another by the combustion tube 6, with complete air-tightness at the crossing points by welding. A plug 9 is placed below to permit the emptying of the boiler 8 when there is need for cleaning and etc.

The boiler 8 is filled with water up to a certain level *aa* (about mid-height) in order that there will be formed an upper evaporation chamber where water vapour can be produced when the fuel has burnt in the cup 7 for a relatively short time. This vapour is led from the summit of the boiler as far as the front entrance of the combustion tube by means of pipe 10 which, by means of its end which is fringed or provided with a perforated rim 11, projects one or several jets of vapour into the said combustion tube. This or these jets draw in a certain quantity of ambient air, the amount of which can be controlled by a plate partially obscuring the space comprised between the distributor 11 and the forward edges of the combustion tube. (The plate is not shown in the drawings.)

To adjust the maximum pressure in the boiler 8, an adjustable valve 12 is placed at any point in the course of the water vapour (on the top of the boiler or on the tube 10 or on any other tube mentioned hereafter, or even in certain cases on the summit of the water reservoir to be described hereafter).

The boiler 8 should have a constant level of water *aa* in order that the production of water vapour may be regular. For this purpose, it is fed with water by a reservoir 13 placed at a small distance above *aa* and provided with a tube 14 with a valve. This tube 14 comprises at its lower part a constant level regulator 15 having a flat closing barrel float or a pointed float.

But in order that the pressure present in the boiler should not bring about the stoppage or even the return of the flow of water coming from the regulator 15, the top of the water reservoir and the top of the regulator 15, both of which are hermetically sealed, are put into communication by tubes 16 and 17 with the top of the boiler in order to obtain a constant equilibrium of the pressures present in 8, 13, and 15.

In a variation of construction, it is possible to omit the water reservoir 13 and use instead a

main water supply which would be connected at the tube 14. Figure 3 shows details of the regulator 15 in which a float 19 carries a rubber seal 20 which closes at outlet 21 of the pipe 22 coming either directly from the main or from a reservoir 18. The float arrangement shown in Fig. 3 is old and well-known in the art.

As the burner should function at low water vapour pressure this maximum pressure can be of the order of 300 grammes per cm.² which corresponds to a height of three metres of the reservoir 18 above *aa*.

Again one could simply arrange the water installation pipe as a fixture on top of the regulator 15, providing that the pressure of the installation is greater than the maximum pressure which can be reached by the steam of the boiler.

Again one could in place of a single combustion tube with cup and with ventilation by a vapour jet, cross the boiler 8 by two or several combustion tubes in parallel, each of these latter having a completely individual installation, that is to say, a combustion cup, a feeding tube for fuel with a funnel, a valve, and a distributor with vapour jet. Likewise one can replace the distributor tubes by a single vapour tube ending in a large single distributor but pierced about with as many holes (or double holes or triple holes) as there are combustion tubes to be ventilated. Any useful details can be added, such as a cleaning trap for the boiler, masses of copper in the cup to increase the spread surface of the fuel, etc.

The dimensions of the complete apparatus are determined by its particular use, such as domestic boiler, cooking stove, industrial furnace and etc.

It goes without saying that the forms, details, dimensions and primary materials can be varied without exceeding the scope of the object of the invention. The heating power of such a burner is very high. The combustion of the heavy fuel is complete stirred up and activated by the jet of water vapour mixed with air, and without any other mechanical or electrical device. The particles of carbon in suspension in the flame or deposited on the walls through which the flame passes, play, at this high temperature, the part of catalysts for decomposition of the water particles, thereby freeing hydrogen.

The combustion tube 6 is described above with a horizontal direction. This direction can be any other required for a particular use, such as for instance oblique or vertical. Likewise, the combustion tube can be curved to direct the flames which come out in a certain direction. This result can be otherwise obtained by the positioning of a flame reflector at the exit. The section of the combustion tube can be round, oval, or otherwise as required.

We claim:

Burner for heavy fuels comprising a horizontally-disposed open-ended combustion tube, a removable cup in the lower part of said tube to receive fuel, a vertical fuel feed tube crossing the combustion tube and terminating at its lower end above the cup, a fuel reservoir above the combustion tube to feed the fuel to the feed tube, a water boiler arranged about the whole length of the combustion tube, a conduit on the boiler conveying water vapour therefrom into one end of the combustion tube, a perforated distributor arranged transversely in one end of the combustion tube and connected to said conduit, and jet forming means on said distributor directed along the combustion tube to direct the water vapour in the form of jets along the combustion tube parallel to the surface of the fuel in the cup, the jets causing a strong gaseous current through the combustion tube which draws in air for more complete combustion of the fuel.
